UNITED STATES PATENT OFFICE

146,193

DESIGN FOR A TRICYCLE

Andrew E. Sukovich, Linden, N. J.

Application February 1, 1946, Serial No. 126,167

Term of patent 3½ years

(Cl. D34—15)

To all whom it may concern:

Be it known that I, Andrew E. Sukovich, a citizen of the United States, residing in Linden, county of Union, and State of New Jersey, have invented a new, original, and ornamental Design for a Tricycle, of which the following is a specification, reference being had to the accompanying drawing, forming a part thereof,

Fig. 1 is a perspective view of a tricycle embodying my new design taken from the front thereof, and

Fig. 2 is a perspective view of the tricycle taken from the rear thereof.

I claim:

The ornamental design for a tricycle, as shown.

ANDREW E. SUKOVICH.
